UNITED STATES PATENT OFFICE.

CORNELIUS S. CLARK, OF NORFOLK, VIRGINIA, ASSIGNOR TO CLARK ENGINEERING CORPORATION, OF NORFOLK, VIRGINIA, A CORPORATION OF VIRGINIA.

INTERNAL-COMBUSTION ENGINE.

Application filed April 3, 1925. Serial No. 20,569.

This invention relates to internal combustion engines and proposes novel means for promoting economy and efficiency in the operation of such engines by controlling the disposition of leakage fluids which ordinarily traverse the joint between cylinder and piston under the urge of the differential pressure existing in the combustion chamber and crank case. These fluids are on the one hand, non-volatile fractions of the fuel which tend to leak downwardly into the crank case, the effect of which is to impair the viscosity of the lubricant, and on the other hand, lubricating oil which is drawn upward from the crank case into the combustion chamber, where it fouls the ignition terminals, and chars, forming a carbon deposit upon the piston and wall of the cylinder head.

The present invention is an improvement over the invention described and claimed in my Patent No. 1,540,602 granted June 2, 1925, in that it has for its object the provision of means employing gaseous fluid pressure applied to the joint between the cylinder and piston in a zone between the fuel entrapping means and the means for intercepting the lubricating oil.

Another object of the invention is the provision of a manifold so constructed as to conveniently furnish both the sub- and super-atmospheric pressures required in the functioning of the device.

Other objects of the invention will be unfolded as the following description of a preferred embodiment thereof proceeds.

In the drawings:—

Figure 1 is a side elevation of an internal combustion engine, parts being in section and parts broken away, showing the device of my invention applied thereto.

Figure 2 is a vertical section through one of the pistons taken along the line 2—2 of Figure 1.

Figure 3 is a section taken along the line 3—3 of Figure 1.

Figure 4 is a section taken along the line 4—4 of Figure 1.

Figure 5 is a section of the lower portion of the cylinder in a slightly modified form of the invention.

Figures 6 and 7 are fragmentary views taken respectively in cross and vertical section of the wrist-pin mounting of the piston.

Referring now in detail to the several figures, the numeral 1 represents a cylinder block having a lower portion 2 which forms the upper half of the crank chamber. The cylinders 3 are supplied with combustible mixture by means of an intake manifold 4, and evacuated by an exhaust manifold 5, said manifolds being preferably cast integrally as shown so as to provide efficient heat transmission by conducting to the intake manifold, for the purpose of pre-warming the combustible charge. Pistons 6 travel in the cylinders 3. Broadly considered, the features above enumerated are old except that for the purpose of carrying out my invention, certain parts are modified in a manner presently to be described.

As has been stated in my application Serial No. 710,882, it is well known that a portion of the liquid fuel now available for use in internal combustion engines is difficultly volatile at low engine temperatures so that it either remains in liquid form or is condensed into liquid after reaching the engine cylinders. Said liquid, or a portion thereof is then forced down past the piston rings upon the compression and explosion strokes of the engine and finds its way into the crank case where it commingles with the lubricating oil, ruining the latter by impairing its viscosity. Not only is the oil thus rendered useless but the liquid fuel with which it is diluted, is wasted.

The present invention is similar to the invention described in my aforementioned application to the extent that the cylinder wall is provided with an upper annular channel 7 extending thereabout, said channel being located at such a zone in the cylinder as will be traversed by the intermediate portion of the piston body but never transsected by the piston ring or rings or the lower end of the piston skirt. Preferably said channel is so arranged as to be an appreciable distance above the lower end of the piston when the latter is at the top of its stroke so as to be substantially sealed from communication with the crank case. Said channel is connected with a conduit 8 which is one of the branches of a conduit 9, the latter communicating with the intake manifold 10, preferably at one side thereof, as shown.

A channel 11, similar to the channel 7 is provided in the cylinder wall, lying in a zone some distance below the channel 7 and also within the limits of the range of move-

ment of the intermediate portion of the piston. The channel 11 is connected by a conduit 13 with the exhaust space within the exhaust manifold 14.

5 It is apparent that the upper channel, 7, is subject to the suction of the intake manifold, while the other channel, 11, is subject to pressure from the exhaust manifold.

10 Upon the explosion of a charge of fuel mixture within a cylinder, the piston being then at the top of its stroke, a portion of the fuel is incidentally forced past the piston ring 15 into the narrow annular space between the piston and cylinder wall below 15 said piston ring. In the operation of my invention, the most of this fuel becomes trapped in the channel 7 and is carried by suction directly into the intake manifold where it forms a proportion of the fuel being drawn into the cylinder. This salved fuel enriches the mixture to such an extent 20 that the carburetor may be adjusted to supply a leaner mixture, an appreciable economy in fuel consumption being thereby effected. In my pending application aforementioned the suction in the upper groove was relied upon solely for preventing the non-volatile fuel fraction from descending below the channel 7, but in this respect it 25 was only in a measure efficient. By the present invention pressure is applied through the channel 11 to the space between the cylinder wall and piston, which supplements the action of the vacuum in the channel 7 30 and forces upwardly any portion of the leakage fuel which may have gotten past said channel.

35 When the piston descends upon its suction stroke, a high degree of vacuum is engendered within the combustion space within the cylinder prior to the admission of a new charge of mixture, which vacuum causes the drawing up of a quantity of oil from those surfaces of the piston wall 40 which have become wet with oil by splash from the crank case. Said oil normally would mix with the leakage fuel as it is drawn off from the channel 7, vitiating it by rendering it unfit for fuel consumption. In 45 my pending application hereinbefore mentioned, provision was made for drawing this upwardly-flowing oil by suction, away from the space between the cylinder wall and piston, and then returning it to the crank case. By the present invention the same pressure 50 which is employed to assist in preventing the descent of fuel into the crank case is utilized in forcing back the film of oil which would otherwise encroach upon the descending fuel.

55 I have found it advantageous to provide a channel 16 below the channel 11, the former functioning as an interceptor for the ascending lubricant. A zone at super-atmospheric pressure is therefore maintained

about the piston between the channels 7 and 16 which completely segregates the oil from the fuel, forcing each of said fluids back in the direction from which it emanated. The piston skirt is of such length as to expose 70 the channel 16 to the crank chamber in the manner shown at 18 in Figure 1 every time the piston reaches the top of its stroke, the surplus lubricating oil being then blown out into the crank chamber by pressure from the 75 channel 11 acting across the bridge 19. It may be desirable to have the interceptor 16 also in constant communication with the crank case. This may be accomplished by means of the passage 35, shown in Figure 2. 80

85 It is essential to the proper working of the system that the intermediate portion of the piston, that is to say, that portion between the piston ring 15 and the lower end of the skirt be reasonably fluid-tight. For this purpose the wrist-pin bushing 20, illustrated in Figures 6 and 7 is made with a closed end and with a cylindrical curvature indicated at 21, conforming to the curvature of the cylinder wall. It has been 90 found desirable also to employ a special ring for assisting in keeping the intermediate portion of the space between the piston and cylinder wall fluid-tight, which ring, in the present instance consists of a relatively 95 broad member 22 surrounding a rib 23 formed in the ring groove of the piston, said member being flanked above and below by thin rings 24 and 25 which extend in a depth direction into shallow grooves at the 100 sides of the rib 23.

105 Although fluid-pressure from any suitable source may be utilized in the practice of my invention, I prefer to employ the exhaust pressure of the engine, and to the end that the present system of fuel and oil conservation may be applied to motors already in use, I have devised a novel form of manifold to be used as a replacement part for the ordinary intake and exhaust manifolds 110 and which is so constructed as conveniently to supply the pressure for the channel 11 as well as the suction for the channel 7. Said manifold consists of an integral casting indicated, as previously stated, at 5 in Figure 115 1, the detailed construction of which is best shown in Figure 3, in which the intake passage 26 and the exhaust passage 27 are preferably formed in an integral casting, the walls of the former passage being warmed 120 by direct conduction from the walls of the exhaust passage. A chamber 28 is formed in said manifold, communicating with the exhaust passage by means of a port 29, the wall of said chamber being provided with 125 threaded openings 30 into which nipples 31 are screwed, the same forming parts of unions by means of which the pressure conduits are connected to said manifold. The wall of the intake passage is provided on 130

either side with a threaded opening 32 carrying a part of the union by means of which the conduit 9 is connected to the intake manifold. As it is necessary to deliver a certain pressure to the channel 11 in order to have the system function properly, means in the form of a valve 33 is provided in the exhaust manifold beyond the cylinders, for creating a slight back pressure in said manifold. As a small degree of pressure is sufficient, the effect of the back pressure upon the operation of the engine is negligible. The valve 33 may be adjustable so as to give more or less back pressure as conditions of operation of the engine may demand.

In Figure 5 I have shown a form of the invention in which the interceptor 16 is made in the form of a spiral groove 34 extending to the bottom of the cylinder. This has the advantage of being constantly in communication with the crank case, so that the surplus lubricant blown into the interceptor by pressure from the channel 11 flows into the crank case continuously instead of at intervals as is suggested by the first described form of the invention.

While I have above shown and described what I believe to be a practical embodiment of my invention, it is to be understood that the invention may be exemplified in numerous other constructions without transcending the scope of the invention.

Having described my invention what I claim as new and desire to secure by Letters Patent, is:—

1. In an internal combustion engine, a cylinder including a combustion chamber, and a crank case, a piston in said cylinder reciprocable relatively thereto and separating that portion of the cylinder wall exposed to the combustion chamber from that part exposed to the crank case, one of said relatively reciprocable members being provided with means constantly overlain by the other for entrapping fuel leaking from the combustion chamber past said piston and with separate means for intercepting lubricating oil leaking past said piston from the crank case, and means for admitting fluid pressure to the space between said fuel trap and oil interceptor, for segregating said leaking fluids.

2. In an internal combustion engine, a cylinder including a piston chamber, and a crank case, a piston in said cylinder reciprocable relatively thereto and separating that portion of the cylinder wall exposed to the combustion chamber from that part exposed to the crank case, one of said relatively reciprocable members being provided with means constantly overlain by the other for entrapping fuel leaking from the combustion chamber past said piston and with separate means for intercepting lubricating oil leaking past said piston from the crank

case, means for admitting fluid pressure to the space between said fuel trap and oil interceptor, for segregating said leaking fluids, and means operating through suction for returning said entrapped fuel to the engine.

3. In an internal combustion engine, a cylinder including a combustion chamber, and a crank case, a piston in said cylinder reciprocable relatively thereto and separating that portion of the cylinder wall exposed to the combustion chamber from that part exposed to the crank case, one of said relatively reciprocable members being provided with means constantly overlain by the other for entrapping fuel leaking from the combustion chamber past said piston, and with separate means for intercepting lubricating oil leaking past said piston from the crank case, means communicating with the exhaust manifold of the engine for admitting fluid pressure to the space between said fuel trap and oil interceptor for segregating said fluids, and suction operated means communicating with said intake manifold for returning said entrapped fuel to the fuel mixture intake of the engine.

4. In an internal combustion engine, a cylinder including a combustion chamber, and a crank case, a piston in said cylinder reciprocable relatively thereto and separating that portion of the cylinder wall exposed to the combustion chamber from that part exposed to the crank case, said cylinder being provided with upper and lower channels, said upper channel functioning to entrap fuel leaking from the combustion chamber past the piston, and said lower channel intercepting lubricating oil leaking past said piston from the crank case, a conduit connecting said upper channel with the intake manifold of the engine, said cylinder being provided with a channel lying in a zone between said upper and lower channels and communicating with the exhaust manifold of the engine for admitting fluid pressure to said zone for segregating said fluids.

5. In an internal combustion engine, a cylinder including a combustion chamber, and a crank case, a piston in said cylinder reciprocable relatively thereto and separating that portion of the cylinder wall exposed to the combustion chamber from that part exposed to the crank case, said cylinder being provided with upper and lower annular channels extending transversely therabout and with a channel in a zone between said upper and lower channels, said upper channel functioning to entrap fuel leaking from the combustion chamber past the piston, and said lower channel intercepting lubricating oil leaking past said piston from the crank case, a manifold for said engine having intake and exhaust passages, said

upper channel being in communication with said intake passage whereby entrapped fuel is returned to said engine by suction and said intermediate channel being in communication with said exhaust passage for admitting fluid pressure to said zone for segregating said fluids.

6. In an internal combustion engine, a cylinder including a combustion chamber, and
10 a crank case, a piston in said cylinder reciprocable relatively thereto and separating that portion of the cylinder wall exposed to the combustion chamber from that part ex-

posed to the crank case, one of said relatively reciprocable members being provided 15 with means constantly overlain by the other for entrapping fuel leaking from the combustion chamber past said piston, and means for admitting fluid at pressure superior to the normal pressure in said fuel trap to the 20 space between said piston and cylinder, between said fuel trap and crank case.

In testimony whereof I have hereunto set my hand.

CORNELIUS S. CLARK.
